UNITED STATES PATENT OFFICE.

CYRUS CHAMBERS, JR., OF OVERBROOK, PENNSYLVANIA.

DOUGH-MIXING MACHINE.

939,392.

Specification of Letters Patent.

Patented Nov. 9, 1909.

Application filed October 4, 1905. Serial No. 281,256.

To all whom it may concern:

Be it known that I, CYRUS CHAMBERS, Jr., a citizen of the United States, residing at Overbrook, in the county of Montgomery and State of Pennsylvania, have invented a new and useful Dough-Mixing Machine, of which the following is a specification.

My invention relates to improvements in machines for mixing dough, and comprises 10 means whereby flour is sifted lightly and automatically into the liquid, such as yeast, milk and water, means whereby the sifted flour is drawn lightly and without material pressure through the liquid, and means 15 whereby the mixture is then aerated by being pulled apart in the air above the liquid. By this operation the flour particles are each completely enveloped in moisture, and held in light contact with one another so 20 that they may fully expand and develop.

My invention comprises improvements in the device described in patent to L. C. Sharpless No. 710,619 dated Oct. 7, 1902.

My object has been to reduce the cost of 25 manufacture of the machine; to improve its working qualities; to increase its durability; to prevent waste of flour; to provide means whereby the machine may be quickly and easily taken apart and put together; to provide means whereby the machine may not be 30 put together wrongly; to provide means whereby the machine may be readily cleaned and whereby it may be made strictly sanitary; to provide means whereby the required 35 work of the machine may be performed in the least possible time whereby an improved quality of bread is produced at minimum labor.

My invention comprises means connected 40 with the bottom of the air chamber for preventing endwise movement thereof; the reduction of the diameters of the shafts with respect to the width of the blades; the relatively increased diameter of each shaft at 45 the gear end thereof; improved means for connecting the separable parts together; means for preventing longitudinal movement of the shafts, and for preventing the leak of material between the shafts and 50 their journal boxes; means at the ends of the shafts distant from the gear end to secure their proper positioning; means for securing the proper relative association of the gear wheels; improved means for adjusting 55 the position of the thermometer; and means connected with the supporting feet for pro-

ducing a yielding, frictional contact with the surface upon which the machine may rest, said tread having such characteristic that it will be slightly elastic, fire proof, impervious to water, and nonshrinkable with age.

Referring to the drawings:—Figure 1 is an elevation of my device. Fig. 2 is a cross-section on line 2', 2' of Fig. 1. Fig. 3 is a plan view of the basin with the superimposing structure removed. Fig. 4 is a plan view of the sifter. Fig. 5 is a longitudinal vertical section on line 5', 5' of Fig. 4, the middle portion being broken away to economize space. Fig. 6 is a side elevation of the spring catch. Fig. 7 is a horizontal section of the thermometer shield and fastener. Fig. 8 is an elevation of the connecting rod catch. Fig. 9 is a vertical section on line 9', 9' of Fig. 8. Fig. 10 is a right hand end elevation. Fig. 11 is a left hand end elevation. Fig. 12 is a perspective view of the thermometer calibrating device. Fig. 13 is a section of sifter shaft through yoke slot. Fig. 14 is a fragmentary vertical sectional view of sifter head, sifter shaft and upper end of air chamber. Fig. 15 is a fragmentary view of the interior end elevation of sifter hopper. Fig. 16 is a fragmentary view of one end of the bottom of the sifter. Fig. 17 is a sectional view of the spring catch in the preliminary locking position. Fig. 18 is a fragmentary view of the gear end of a mixing shaft. Fig. 19 is an end elevation of Fig. 18.

Similar numerals refer to similar parts throughout the several views.

My device comprises the basin portion 1 with the air chamber portion 2 detachably connected therewith. The air chamber portion 2 is open at the top and is adapted to have seated in said opening the sifting hopper 3. Between the basin 1 and the air chamber member 2 are located the journal boxes for the shafts 4 and 5, provided with the sets of mixing blades 6 and 7 respectively. These shafts are connected with the coöperating gears 8 and 9, operated by the handle or winch 10, so that said shafts will be rotated in opposite directions as indicated by the arrows in Fig. 2.

Each mixing shaft has been materially modified and improved by reducing its diameter, while the mixing blades have been made wider at their junction with the shafts than the diameter of the shafts as shown in

Fig. 2, so that the dough will adhere with more tenacity to the wide blades than to the small diameter shaft. Hence in the passage of the blades past the small shafts the dough is drawn from the shafts. This prevents the winding of the dough around said shafts, which is frequently the case in dough mixers now in common use. By preventing the dough from adhering to and winding about the shafts it is obvious that a more thorough mixture of the dough is secured, since the blades of one shaft in moving upward past the opposite shaft lift the dough out of the liquid and drag it away from the shaft and carry it up into the air chamber, where it is drawn apart by the now separating blades.

The mixing blades are so arranged that the end ones on both shafts, next to the ends of the basin, operate in the same plane so as to mix the dough clear to the end of the basin on either side. For this reason the shafts must be properly associated, that is geared relatively, so that these blades shall not interfere with one another. As these shafts are frequently removed from the bearings, it is desirable to provide means whereby the inexperienced can and must properly replace them.

In order that the two gear wheels 8 and 9, which are cast integral with the shafts 4 and 5 respectively, may always be so meshed as to allow these extreme end knives to pass one another, that is without interfering with one another, I have provided a projecting rim 11 on the gear wheel 9 upon which the winch is cast, with a notch in it preferably of the width of two teeth in the gear wheel. On the side of wheel 8, I provide a projection 12, two teeth in width, extending beyond the length of the teeth so as to enter into the notch previously described, whereby when the wheels are properly meshed the projection 12 will enter the opening in the rim 11 of wheel 9. Thus it will be seen that only when the wheels are meshed in the proper relative positions, rim 11 and projection 12 will not interfere. In any other relative positions of said gears, the projection 12 will strike rim 11 and interfere with the operation of the machine, thereby warning the operator that the machine is not properly assembled.

The journal boxes and the shafts rotating therein are constructed and proportioned relatively so as to prevent improper assembling of the various parts, and so as to reinforce the operative parts approximate the point of greatest strain, and so as to prevent the leak of material between said shafts and surrounding journal boxes as will be more particularly described below.

The air chamber member 2 is provided with outwardly projecting lugs 28 which in turn are provided with downwardly projecting lugs 40 (see Figs. 1, 6, 10 and 17) to em-

brace the upper margin of the basin member 1, to secure perfect adjustment of said two members and to prevent end movement thereof. These lugs 40 project below the basin joint and beyond the line thereof, so that they lap down over the basin under the lugs 28, whereby they are hidden from view. The faces of lugs 40 which engage with the basin, are chilled and are thus made to fit accurately without additional machine work, and without interfering with the chilling of the contacting surfaces of the chambers. The upper edge of chamber 1 and the lower edge of chamber 2 which come into engagement with each other, are cast with chilled surfaces to secure a substantially tight, non-leakable joint between said two chambers, without further planing or machine work. Improved spring catches are also provided to maintain efficient engagement between said basin member 1 and air chamber member 2, which catches shall hereinafter be described in detail.

The top of air chamber 2 is open, and adapted to receive the sifter hopper 3. This sifter hopper 3 is a separate chamber readily removable from the top of the air chamber 2. It is provided with flanges 21 at each end to embrace the ends of air chamber 2 and to prevent endwise movement. These flanges 21 also serve as supporting feet for the sifter hopper when the same is not resting upon the air chamber. Spring catches are also provided to lock the sifter member upon the air chamber member in the operative position. Sifter hopper 3 is provided with the perforated bottom 32. The shaft 13 is journaled in the opposite ends of said sifter hopper. The oscillating yoke or mixing member 14 has an intermediate horizontal extension with its two ends at right angles therewith; said ends being movable in transverse slots in shaft 18, the angles of the yoke or mixing member between the vertical parts and the intermediate horizontal part are squared out, as shown in Fig. 14, so as to insure the dislodgment of the flour close to the head of the sifter hopper. Shaft 13 is connected by crank 15 and connecting rod 16 with the gear 8 whereby an oscillating movement is given thereto, causing the sifter yoke to sweep with oscillatory movement the perforated curved bottom 32 of the sifter hopper 3. The connecting rod 16 is provided at each end with the aperture 39 for receiving the wrist pin of crank 15 and the wrist pin on gear wheel 8. Secured to the edge of the connecting rod 16 is the gravity actuated gate 41, provided with the slot 38 through which passes the screw 37. The wings or projections 41^a extend on either side of the rod 16, and form a channel therefor. At the lower end of the gate 41 is the horizontal projection or lug 36. These gates are of metal and have a free movement, with re-

spect to the connecting rod 16, limited by the extent of slot 38 through which screw 37 passes. In engaging the rod with the wrist pins it is simply necessary to place the edge 5 of the connecting rod against the wrist pin and slide it downward. When the wrist pin encounters the gate or the lug thereon the gate is raised, and the wrist pin is admitted to the recess 39, whereupon the gate falls 10 securing the pin in said recess.

On the inner sides of the sifter hopper 3, around the upper side of the journaled boxes of shaft 13 are provided the semi-circular projections 17 which serve as bearings for 15 taking the end thrust of the sifter shaft 13, and also the side thrust of the yoke or mixing member 14. The pressure of projection 17 on the side of yoke or mixing member 14 forces the yoke down at the opposite end, 20 so as to keep it in contact with the perforated bottom of the sifter hopper. The shaft 13 has a vibratory motion imparted to it, which causes it to move up and down in its journal boxes provided there be any lost 25 motion between said shaft and its journal boxes. This serves to pump the flour out through the journal boxes. To prevent this objectionable condition I provide at the opposite end of the shaft from that to which 30 the crank is secured, a journal box closed at its outer end so that no leak is possible therethrough. This structure is indicated at 18 in Figs. 1 and 4. At the crank end of the shaft I project the journal box beyond the 35 face of the sifter head and provide a recess 19 in the hub of the crank to receive said box, as indicated in Fig. 14 whereby the course of the flour is out through the box over the end of the box between it and the 40 side of the crank and back over the box and within the recessed hub of the crank, thus making a circuitous route for the flour to pass, this will serve to take up the leakage and practically prevent the escape of the 45 flour.

Each head or end of the sifter hopper 3 has cast upon it two inwardly projecting lugs 20, opposite the feet 21, and which are adapted to rest upon the upper curved edge 50 of the air chamber member 2. These lugs serve to maintain the sifter hopper 3 in its proper position with respect to the air chamber, up and down as well as sidewise. The longer feet 21 extending downwardly 55 over the outer ends of the air chamber prevent endwise movement between hopper and air chamber. The lugs 20 also serve to bring the perforated plate of the sifter to its exact position relative to the sifter heads, 60 and to keep it in position while soldering, there being recesses cut in the perforated metal to receive said lugs as shown in Fig. 16. The perforated bottom 32, it will be 65 seen, passes beneath the ends or heads of the sifter hopper, the perforations extending the

entire length of said hopper, so that the flour will be sifted to the extreme ends of the mixing chamber. The upper end of the air chamber upon which rests the sifting chamber is bent outwardly so as to catch 70 any flour that would otherwise lodge upon the upper edge of said air chamber, were it straight.

The spring catch used to lock the various parts of the machine together has the following novel features of construction. As 75 these catches are all similarly constructed, a description of one will suffice for all.

Referring to Figs. 6 and 17 the U-shaped spring 25 is pivotally secured by pivot 30 to 80 a fixed lug on one of the members of the machine, say the basin member 1. The other end of the spring 25 is secured by pivot 29 to a cam member 24 provided at its upper end with a ring 52 for convenience in 85 manual operation. Cam member 24 is also provided with a projecting point 26 and a projecting horn 27.

Referring to Fig. 17 member 24 is thrown into what may be termed a preliminary locking position. When member 24 is lifted upwardly toward lug 28 of member 2, the projecting horn 27 encounters lug 28, until the projecting point 26, engages the upper side of said lug 28. The further tilting 95 movement of member 24 causes the throwing of said member 24 over the center, that is, over the line of strain between said pivots 29 and 30 with respect to point 26, in the position shown in Fig. 6. The horn 27 is 100 at the same time carried away free from engagement with lug 28. The ring 52 will rest against the vertical wall of member 2. By this construction it will be seen that there is no rubbing or friction between point 105 26 and lug 28, and therefore no possibility of wear which is so often an objection to spring catches of this general character. It is obvious that when the member 24 is thrown over the center as above described, 110 it will remain in such position, being so held by the tension of spring 25, until said member 24 is again manually operated to move in the opposite direction over the center into the unlatching position. The side projections 115 24^a on member 24 are adapted to encounter the springs 25 to prevent the member 24 from upsetting or falling too far back. Without this it would be possible for the horn 27 to miss the lug 28 in bringing 120 the catch to the closed position.

On the near end and on the near side of the air chamber 2 is provided the handle 53 for the purpose of enabling the operator to steady the machine on the table while operating it, and to take the reaction of the strain in turning the crank, whereby not only is the machine steadied but the operator steadied also, by the action and reaction of force required to work the machine. 130

This handle is secured by a bracket 54 cast upon the near head of the air chamber extending out far enough to receive the end of the handle which handle is far enough 5 from the side of the air chamber to admit of the hand going between the handle and the air chamber. The other end of the handle is supported by a small bracket 55 secured to the side of the air chamber near 10 the middle thereof as shown in Fig. 1.

To prevent leakage around the journals of the mixing shafts I close the outer end of the boxes opposite the gearing on the shaft, by placing over the end thereof a circular plate, one-half of which is preferably formed integrally with the basin member the other half with the air chamber member, so that when the two are brought together the opening is entirely closed. These closed journal boxes are indicated by the numerals 56 15 and 57 on Fig. 3.

To prevent the endwise slip of the shafts in their journal boxes I provide the collars 58 and 59 inside the chamber at the end approximate the gearing, as shown in Fig. 3, 20 and also in Fig. 18. These collars also serve to prevent the moisture and dough from working out through the journal boxes at the gear ends of the shafts.

I provide the following improved means 25 for securing a thermometer to the basin member so that the same may be properly calibrated whether the mercury stands normally below or above the position I have indicated 30 as required for bread making. This thermometer 33 is secured in the recess formed by the surrounding flange 35, see Fig. 11. I provide a piece of sheet metal 46, see Fig. 12, having a vertically extending portion, provided with series of holes 47 to receive the hook of the thermometer tube 33. From the vertically extending portion of piece 46 extend a pair of horizontal arms 48 adapted to wrap around the thermometer tube once 40 and then engage in suitable apertures or recesses in the flange 35. A second set of shorter arms 49 are provided to further secure the thermometer tube to piece 46. The strip 34 engaging in suitable recesses or apertures in flange 35 serves to maintain the lower end of the thermometer tube in position. The range of temperature within 45 which the yeast plant will best develop is shown by the indication marks 95--F, and 50 70--F, see Fig. 11. The series of holes 47 afford means for shifting the position of the thermometer tube vertically with respect to the indication marks on the basin, in calibrating.

The basin member 1 is provided with the supporting legs 43 having treads 45 which have the characteristic of being slightly elastic, heat resisting, impervious to water and nondeteriorating with age, and which shall 55 produce a frictional contact with the table

upon which the machine may rest. After a careful study of such substances as I was familiar with, and many experiments among which were rubber bumpers, wooden bumpers, asbestos bumpers, fiber and rubber bumpers, I found by many tests that common cork came the nearest to filling all the requirements. It is elastic, it is comparatively impervious to water, it resists a higher temperature than many of the other materials 70 enumerated, without being injured. It does not shrink or otherwise deteriorate with age, and yet offers a frictional resistance to the table, thus fulfilling all the requirements. This cork is attached to the foot by casting 75 a dovetailed circular recess 44 in the body of the foot, and compressing therein cork treads 45 which are cut conically, compressed by a machine, and forced into the recess, where the cork expands, filling the inner and larger end 80 of same, and projecting out to form a cushion tread for the foot. I find that this is a very valuable improvement in making the machine silent when set upon the table, and 85 greatly steadying it in the operation of turning. 90

The operation of my device is as follows: Before assembling the various elements, the basin member 1 or liquid chamber is supplied with a suitable quantity of liquid such 95 as water, milk and yeast. The various elements are then assembled and flour is supplied to sifter hopper 3. The handle 10 is turned in the clockwise direction as indicated by the arrow in Fig. 10, this being 100 the natural direction of rotation. By turning the handle in the clockwise direction, the mixing blades are turned in the direction indicated by the arrows in Fig. 2. That is, the blades in the lower position approach 105 each other and separate only in the elevated position. Assuming that the liquid in basin 1 stands at a level about half way between the top and bottom of basin 1, the blades 6 and 7 will approach each other beneath the 110 level of the liquid, meeting at a point considerably below the surface thereof and separating entirely above the surface of the liquid in the atmosphere of air chamber 2. This insures an efficient mixing of the flour 115 with the liquid and by pulling it apart in the atmosphere above the liquid the same is thoroughly aerated in the atmosphere of the air chamber. Fresh air is being constantly supplied to air chamber 2 through 120 the open spaces between the sifting hopper 3 and the top of air chamber 2.

While the blades are being rotated as above described, motion is communicated from gear 8 to crank 15, to rock shaft 13 and sifter bar 14, so that the relation of movement between sifter bar and mixing blades is always constant, that is, the faster the blades rotate the faster the sifting bar 125 oscillates, so that the faster the mixing takes 130

place the faster is the flour fed to basin 1. The formation of the bottom of basin 1, that is, the intermediately disposed ridge 1^e, cooperates in the mixing operation of blades 5 and 7, in bringing the particles of dough together, so that the blades will carry the same upwardly out of the liquid and pull or shred it apart in the atmosphere of air chamber 2.

10 By providing the required predetermined quantities of liquid and flour, the thorough mixing and aeration of the dough is practically automatic, and always uniform.

By the above described mechanism the 15 flour is sifted lightly and automatically into the liquid. It is then drawn lightly and without material pressure through the liquid by the mixing blades. It is then lifted out of the liquid and pulled apart by

20 the oppositely moving mixing blades in the air chamber above the liquid and thereby aerated. By this operation the flour particles are each completely enveloped in moisture, and held in light contact with one another, so that they may fully expand and develop.

25 When the dough is sufficiently mixed, the various parts of the machine are separated, the shafts removed, and the dough clinging to the shafts and mixing blades is scraped back into the basin 1. The lug 42, provided with a depression in its upper surface, is a convenient means for supporting one end of the shaft while the operator holds the other end, during the scraping operation. The dough thus contained in the 30 basin 1, is then suitably covered and set aside in an enveloping atmosphere of proper temperature, indicated by the thermometer, until the said dough has sufficiently risen.

40 It is to be noted that the thermometer is clamped against the outside of the metallic basin 1. It is exposed to the outside atmosphere, that is the atmosphere enveloping the said chamber. Being in contact with 45 the basin, the metal of which being a good conductor, it is distinctly affected by the temperature of the dough. It therefore serves to register not the temperature of the enveloping atmosphere alone, nor that of

50 the dough alone, but indicates rather the combined effect of contents of basin and enveloping atmosphere, which enables the operator to secure much more uniform results.

What I claim is:—

55 1. In a dough mixing machine, the combination of a mixing vessel and mixing mechanism therein, said mixing mechanism comprising a pair of parallel rotatable shafts provided with interdigitating mixing blades 60 extending nearly the distance between said shafts, said blades integral with their supporting shafts and having their transverse extensions adjacent the shaft greater than the shaft's diameter and a filleted joinder be-

tween blade and shaft, as and for the purpose specified. 65

2. In a dough mixing machine, the combination of a mixing vessel, a pair of co-operating mixing elements operating therein, said elements comprising parallel shafts, 70 each with radiating blades spirally arranged, the blades having enlarged shoulders adjacent the supporting shaft and tapering toward the outer ends to facilitate carrying the dough upwardly and tearing it apart in 75 the air.

3. In a dough mixing machine, the combination of a liquid containing basin, two sets of mixing blades operating therein, means for moving one set of blades toward the 80 other beneath the liquid and for causing the movement of one set away from the other above the liquid, means for sifting flour automatically into the liquid, the proportion, position and operation of the mixing 85 blades being such as to draw the flour lightly through the liquid and then lift the resultant dough out of the liquid and away from the blade actuating means and then pull it apart in the air above. 90

4. In a dough mixing machine, the combination of a liquid containing basin, a pair of parallel shafts, each provided with mixing blades wider at the shaft, than the diameter of the shaft, said width being in a direction transverse the axis of the shaft, and means for moving the shafts simultaneously so that the blades of one shaft will approach the blades of the other beneath the liquid, and separate in the air above the liquid. 95

5. In a dough mixing machine, the combination of a liquid containing basin, a pair of parallel shafts, each provided with mixing blades set transversely thereto wider at the shaft end than the shaft diameter, means for moving the shafts simultaneously so that the blades of one shaft will approach the blades of the other beneath the liquid and separate in the air above the liquid, means for sifting flour into the liquid containing 100 basin, and means for coupling the operation of the sifter and rotating shafts. 105

6. In a dough mixing machine, the combination of a pair of mixing shafts provided with mixing blades, the blades narrow in direction of the axes of the shafts and broad transversely and adjacent the shafts, and tapering thereto and therefrom, as and for the purpose specified. 110

7. In a dough mixing machine, the combination of a basin member and an air chamber member adapted to superimpose the basin member forming a single chamber, the upper edge of the basin and the lower edge of the air chamber which engage with each other, being cast with chilled surfaces to form a substantially tight nonleakable joint between said members, and lugs projecting 115 120 125

from one member to overlap the sides of the other member to secure proper coöperation of said chilled surfaces.

8. In a dough mixing machine, the combination of a pair of mixing shafts provided with mixing blades, the blades narrow in direction of the axes of the shafts and broad transversely and adjacent the shafts, and filleted at the junction with the shafts.

10 9. In a dough mixing machine, the combination of a basin member, a pair of shafts having mixing blades, coöperating gear wheels connected with said shafts, the journaled portions of the shafts at the gear 15 ends thereof having diameters greater than the diameters of the extension of the shafts between their journals.

10 10. In a dough mixing machine, the combination of a basin member and an air chamber member adapted to be disengageably joined together to form a single substantially non-leakable chamber, a pair of shafts having radially extending blades, split journal boxes for said shafts formed between the basin and air chamber members, said journal boxes closed about the ends of the shafts at one end of the chamber, the shafts projecting through the journal boxes at the other end of the chamber, and provided with collars integral therewith adjacent the last mentioned journal boxes to prevent longitudinal movement and also to prevent leakage.

11. In a dough mixing machine, the combination of a basin member, a pair of shafts provided with mixing blades, journal boxes for said shafts, the shafts at one end and their corresponding journal boxes having a diameter less with respect to one, and greater with respect to the other, than the diameter of the main portion of said shafts, to prevent interchanging of the shafts with respect to the journal boxes.

12. In a dough mixing machine, the combination of a basin member, and an air chamber member disengageably connected together, one member provided with lugs adjacent the other member, spring catches coöperating with said lugs for securing said members together, said catches comprising a spring pivotally secured to one of said members, a cam member pivotally secured to the spring, said cam member provided with a projecting point and a projecting horn approximate thereto, the said parts being proportioned and associated so that the cam member shall have a spring controlled, over-the-center frictionless engagement with its coöperating lug.

13. In a dough mixing machine, the combination of a basin member, and an air chamber member disengageably connected together, one member provided with lugs adjacent the other member, spring catches coöperating with said lugs for securing said

members together, said catches comprising a spring pivotally secured to one of said members, a cam member pivotally secured to the spring, said cam member provided with a projecting point and a projecting horn approximate thereto and a side projection for encountering the spring to prevent upsetting, the said parts being proportioned and associated so that the cam member shall have a spring controlled, over-the-center frictionless engagement with its coöperating lug. 75

14. In a dough mixing machine, the combination of a basin member and means for mixing the material therein, a sifter hopper for delivering to the basin member having an oscillating yoke and a shaft for actuating the same, and projections on the heads of the hopper engaging the upper extensions of the yoke, as and for the purpose specified. 80

15. In a dough mixing machine, the combination of a mixing basin and mixing mechanism operating therein, a sifter hopper for delivering to the basin, a sifter member in said hopper, having an intermediate horizontal extension and end extensions at right angles thereto, a shaft for engaging said sifter member and operating the same, said shaft provided with apertures for receiving the end extensions of said sifter member and projections provided on 95 the inner sides of the hopper heads for engaging the ends of the sifter member above the shaft for taking the side thrust of the sifter member. 85

16. In a dough mixing machine, the combination of a basin member and sifter hopper for delivering thereto, the sifter hopper comprising end members or heads, and a connecting sheet metal portion forming bottom and sides, the bottom part being perforated throughout its extension, and recessed at the ends, the heads provided at their lower sides with lugs for coöperating with the recesses in the perforated bottom to facilitate in assembling said parts. 100 105

17. In a dough mixing machine, the combination of a basin member and a sifter hopper for delivering thereto, the sifter hopper comprising end members or heads, and a connecting sheet metal portion forming bottom and sides, the bottom part being perforated throughout its extension, and recessed at the ends, the heads provided at their lower sides with lugs adapted to serve as supporting feet to said hopper. 110 115 120

18. In a dough mixing machine, the combination of a basin member, a pair of shafts with mixing blades operating therein, the end blade of each shaft traveling in the same plane, gear wheels for causing the rotation of the shafts in opposite directions, and recess and projection means, connected with said gear wheels, for insuring their proper relative association. 125

19. In a dough mixing machine, the com-

- 5 combination of a basin member, an air chamber member separably connected therewith, lugs secured to the air chamber member for preventing end movement with respect to the 10 basin member, spring catches for disengageably securing said two members together and a handle secured to the air chamber member to take the reaction of the strain in operating the machine.
- 10 20. In a dough mixing machine, the combination of a mixing basin, mixing mechanism operating therein, a handle and elastic, non-deteriorating, heat resisting treads, associated with the basin and forming co-operating 15 means in connection with the operator and the table supporting the basin for steady- ing it and maintaining its position, during the operation of the mixing mechanism.
- 20 21. In a dough mixing machine, the combination of a basin member, a handle thereon, winch operated mechanism for mixing dough in the basin and supporting feet for the basin member having cork treads as and for the purpose specified.
- 25 22. In a dough mixing machine, the combination of a basin member, an air chamber member disengageably connected therewith, spring catches for securing said two members together, winch operated mechanism for 30 mixing the dough in the basin, a handle se-

cured to the machine to be grasped by the operator for taking the reaction of the strain in operating the winch, and supporting feet for the basin member having cork treads.

23. In a dough mixing machine having 35 co-operating crank shafts, disengageable means for operatively connecting the same, comprising a connecting rod recessed at each end and provided with gravity actuated gates for closing the recesses, said gates provided with shoulders to encounter the wrist pins of the cranks when bringing the rod into position.

24. In a dough mixing machine, comprising 40 a mixing chamber and a sifting hopper removably related thereto, the sifting hopper having a crank shaft and a sifting bar, the mixing chamber having a crank shaft and mixing blades, disengageable means for operatively connecting said shafts, comprising 45 a connecting rod recessed at each end and provided with gravity actuated gates for closing the recesses, said gates provided with shoulders to encounter the wrist pins of the cranks when bringing the rod into position.

CYRUS CHAMBERS, JR.
